CLAIM

I claim the ornamental design for a mounting bracket, as
substantially shown and described.

DESCRIPTION

FIG. 1 is an upper isometric view of a mounting bracket;

FIG. 2 is a lower isometric view thereof;

FIG. 3 is a top view thereof;

FIG. 4 is a bottom view thereof;

FIG. 5 is a rear view thereof;

FIG. 6 is a front view thereof;

FIG. 7 is a left side view thereof; and,

FIG. 8 is a right side view thereof.

The broken lines in the drawings depict portions of the
mounting bracket that form no part of the claimed design.
